CLAIM

The ornamental design for an intelligent interactive panel as shown and described.

DESCRIPTION

FIG. 1 is a front perspective view of an intelligent interactive panel showing the claimed design;

FIG. 2 is a rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of a region 9 shown in FIG. 1;

FIG. 10 is an enlarged view of a region 10 shown in FIG. 1;

FIG. 11 is an enlarged view of a region 11 shown in FIG. 1;

FIG. 12 is an enlarged view of a region 12 shown in FIG. 2; and,

FIG. 13 is an enlarged view of a region 13 shown in FIG. 2.

The even-dash broken lines, showing multiple buttons on the front side and portions of the rear panel in the figures, represent portions of the intelligent interactive panel that form no part of the claimed design. The long-dash short-

(Continued)

dash broken line boxes and lead lines represent the extents of the detail views and form no part thereof.
